METHOD OF TREATING FIBROUS PULP

George L. Bidwell, Riegelsville, Pa., assignor to
Riegel Paper Corporation, New York, N. Y., a
corporation of New Jersey

Application June 26, 1940, Serial No. 342,455

2 Claims. (Cl. 210—199)

This invention relates to a method of treating pulp and more particularly to a method of de-watering pulp.

In the present invention I provide a method whereby a batch of pulp may be brought to a predetermined consistency. In paper making it is frequently necessary to provide large batches of stock of predetermined consistency. The present practice is to circulate the pulp through a trough, tub or chest which is made very deep to obtain capacity and remove a part of the water from the pulp while it is being circulated.

One method now in use is to employ an octagon shaped washing cylinder that is about one-half submerged in the pulp when in operation. Another method is to employ a star shaped washer. Both of these methods are open to several objections. Neither of them will dewater the stock sufficiently rapid to make their use practical. The star shaped washer is open to the further objection that it displaces too much stock and reduces the capacity of the trough.

In dewatering stock according to my method, I employ a round cylinder of relatively small diameter which is completely submerged in the pulp. The cylinder is provided with a facing of wire netting or other suitable foraminous material. As the stock circulates in the trough and the cylinder rotates, the stock forms a mat on the exterior of the cylinder and a portion of the water contained in the stock passes through the facing into the cylinder and thence to a drain.

The stock in slush form (of thin consistency) is pumped from a bleacher or screen chest into the circulating trough. The dewatering cylinder discharges through the wall of the trough into a suitable drain. The stock is circulated from the outlet end of the trough through a refining engine and returned to the inlet end of the trough. The submerged cylinder is slowly revolved in the direction of flow of the stock and a mat formed on the cylinder. The mat so formed is washed off as the cylinder passes the top center by the force of the flow of stock traveling toward the outlet.

In the accompanying drawings I have shown one embodiment of the apparatus suitable for use in practicing the process and forming a part of the invention. In this showing:

Fig. 1 is a plan view;

Fig. 2 is a side elevation;

Fig. 3 is a transverse, vertical, section view in line 3—3 of Fig. 1; and

Fig. 4 is a similar view on line 4—4 of Fig. 3.

The reference numeral 1 designates a trough

through which the pulp is circulated and which may be of any suitable size and shape. The trough is preferably made deep to permit it to handle large batches of stock and it may be made U-shaped as shown, for convenience of assembly or of any other desired shape. The trough is provided with an inlet end 2 and an outlet end 3 forming two legs 4 and 5 connected by section 6. As shown (see Fig. 2) the bottom of the trough may incline downwardly from the inlet end 2 to the central section 6 as indicated at 7 and between the outlet 3 and the central section 6, the bottom of the trough may be inclined downwardly as indicated at 8. The inclined bottom insures thorough circulation of the entire body of the stock, but if desired a trough of the desired capacity having a horizontally arranged bottom may be used. The outlet end 3 of the trough is connected to a pump 9 through a pipe 10 and the circulating pump 9 is driven by a suitable motor 11. From the pump a discharge pipe 12 leads to the inlet end of a refining engine 13. The refining engine may be of any of the standard types now employed by paper-makers for grinding stock. As illustrated and as generally constructed, it is formed of a conical shell lined with knives (not shown) in which is arranged a revolving plug (not shown) carrying knives which cooperate with the knives of the shell to produce a grinding action. The outlet end of the refining engine is connected to the inlet end of the trough by a pipe 14.

Within the trough and adjacent the outlet end I provide a cylinder 15 of relatively small diameter, compared to the depth of the trough, which is provided with a closed end 16 and is open at the other end. The interior of the cylinder communicates with a drain pipe 17 extending through the wall of the trough and having a control valve 18 arranged therein. The cylinder is adapted to rotate and may be driven from a motor 19 and by means of a belt 20. The belt passes over a pulley 21 on the motor shaft and over a pulley 22 mounted on the shaft 23 of the cylinder. A plurality of spiders 24 are mounted on shaft 23 and they support a facing 25 which is preferably formed of an inner layer of relatively coarse wire and an outer layer of finer wire. A collar 26 is arranged on the wall of the trough adjacent the open end of the cylinder and a similar collar 27 is carried by the cylinder and abuts or engages the collar 26. A packing strip 28 surrounds these two collars and serves to prevent loss of stock.

In operation the pulp in slush form is pumped into the circulating trough. In a specific em-

bodiment of the invention employing a trough of 3500 pounds capacity, I employ a cylinder 15 of 30" diameter and 56" face. The cylinder is revolved at a speed of from 30 to 35 R. P. M. and as the stock is circulated through the trough by the pump 11, it forms a mat on the facing 25 of the cylinder and the water drained from that portion of the stock which forms the mat flows into the cylinder and to drain pipe 17. The thickness of the mat formed on the cylinder is controlled by valve 18. Care must be taken not to form too thick a mat or the capacity of the dewatering device will be diminished. The drain pipe 17 is provided with a vent pipe 30 extending to the full height of the trough. As the cylinder 15 slowly revolves, the dewatered pulp is removed from its face at top center by the force of the stock flowing toward the outlet end 3 of the trough.

With apparatus of the size and dimensions heretofore described, I have found it possible to bring stock from a 2½ to 3% consistency to a consistency of 4½% in twenty minutes total time. This time is computed from the time when the pulp is first started until the trough is filled with 3500 pounds of 4.5% consistency pulp. The dimensions heretofore given of the specific embodiment are of course merely for the purpose of illustration and are not intended to be restrictive. Likewise I have found that the best results are obtained when a coarse wire netting is first arranged on the cylinder and covered with a finer wire screen. For this purpose I have employed a #14 backing wire with a #30 facing wire.

I claim:

1. The method of dewatering pulp used in the manufacture of paper to reduce it to a desired consistency which comprises delivering the pulp to be dewatered to a container having an inlet end and outlet end, flowing the pulp through the container over a foraminous revolving cylinder arranged between the inlet end and the outlet end, the cylinder being entirely submerged in the pulp whereby a mat is formed on the cylinder and removed therefrom by the flowing pulp as the cylinder is revolved, withdrawing water from the interior of the cylinder, withdrawing the pulp from the container at the outlet end after the pulp has passed over the cylinder, returning the pulp to the container at the inlet end, and continuing the recirculation of the pulp until it has reached the desired consistency.

2. The method of dewatering pulp used in the manufacture of paper to reduce it to a desired consistency which comprises delivering the pulp to be dewatered to a container having an inlet end and outlet end, flowing the pulp through the container over a foraminous revolving cylinder arranged between the inlet end and the outlet end, the cylinder being entirely submerged in the pulp whereby a mat is formed on the cylinder and removed therefrom by the flowing pulp as the cylinder is revolved, withdrawing water from the interior of the cylinder, withdrawing the pulp from the container at the outlet end after the pulp has passed over the cylinder, passing the pulp through a refining engine, returning the pulp to the container at the inlet end, and recirculating the pulp until it has reached the desired consistency.

GEORGE L. BIDWELL.
